United States Patent Office

Des. 181,748
Patented Dec. 17, 1957

181,748

LUGGAGE CARRIER

John G. Pawly and Anthony T. Zagwyn, Delavan, Wis.,
assignors to A. J. Industries Corporation, Delavan, Wis.,
a corporation of Wisconsin

Application February 25, 1957, Serial No. 44,979

Term of patent 14 years

(Cl. D14—27)

Fig. 2

Fig. 1 is a perspective view of the luggage carrier, embodying our new design.

Fig. 2 is a side elevation.

Fig. 3 is a section on line 3—3 of Fig. 4.

Fig. 4 is a top plan view.

Fig. 5 is a rear end view.

Fig. 6 is a section on line 6—6 of Fig. 4.

The broken line showing of portions of an automobile are for purposes of illustration only.

We claim:

The ornamental design for a luggage carrier, as shown and described.
